UNITED STATES PATENT OFFICE.

OLOF N. TEVANDER AND ARTHUR MANIERRE, OF CHICAGO, ILLINOIS; GEORGE MANIERRE EXECUTOR OF SAID ARTHUR MANIERRE, DECEASED.

CLOSURE.

1,117,147.

Specification of Letters Patent. Patented Nov. 10, 1914.

Application filed June 13, 1910. Serial No. 568,580.

To all whom it may concern:

Be it known that we, OLOF N. TEVANDER and ARTHUR MANIERRE, citizens of the United States, residing at Chicago, in the county of Cook and State of Illinois, have invented a certain new and useful Improvement in Closures, of which the following is a full, clear, concise, and exact description, reference being had to the accompanying drawings, forming a part of this specification.

The object of our invention is to provide for so fastening a cap over the mouth and about the neck of a milk-bottle, jelly glass or jar, perfume bottle, and the like, for sealing it, as to avoid the use of any form of stopper to enter the mouth and to facilitate the sealing operation while rendering the removal of the cap easy and convenient.

In practising our invention we cover the mouth of a bottle or jar with a cap having a skirted portion extending about the portion of the bottle below its mouth and a tubular fastening band tightly surrounding the skirt of the cap. The ends of this tubular fastening band are preferably in telescoping engagement whereby the ends are tightly engaged with each other to hold the band in tight engagement with the closure skirt, though the invention is not to be limited to this telescoping formation of the band. By making the fastening band of tubular formation a variety of advantages are secured as compared with the results which would follow the use of a solid band. By the use of a hollow band the band is enabled to be firmly applied to all portions of the closure notwithstanding the irregularities in the formation of the bottles or jars since the bands may be subject to compression where the bottles or jars bulge more. Then again, the tubular bands will adapt themselves to the irregularities in the closure so that the necessary tight fit between the closure and the bottle is secured by the hollow band that thus adapts itself to maintain the tight engagement between the closure and the bottle. As the invention is preferably practised the fastening bands are made of substantially non-resilient material so that after they have

once been applied to the closure they cannot be removed from engagement therewith for the purpose of unwarranted access to the bottle without detection since the fastening band, if made of non-resilient material, will not spring back in shape after having once been forced. In accordance with one feature of our invention, but to which feature the invention is not to be limited, the skirted portion of the closure has an outsetting extension and the tightening ring has a formation in gripping engagement with this extension and while this feature is preferably practised with a tightening ring which is hollow, such feature is not to be limited to the employment of a hollow tightening ring.

Referring to the accompanying drawings, Figure 1 is a plan view of one of various forms of machines suitable for fastening the metal band or ring about the skirt portion of a cap or closure for sealing therewith a bottle or the like in accordance with our invention; Fig. 2 is a perspective view of a suitable form of cap or closure to be used for the sealing purpose, and Fig. 3 is a similar view of the cap or closure with a metal band or ring encircling it, ready to be applied to a bottle to be sealed; Fig. 4 is a broken perspective view showing a neck of a milk bottle sealed in accordance with our invention and employing for the purpose one of various usable forms of metal bands, and Fig. 5 is a similar view of the same showing a wire forming the metal cap-fastening band after being crimped by squeezing it; Fig. 6 is a plan view of a tapered strip of sheet metal suitable for forming a tubular metal fastening band like that in Fig. 4, and Fig. 7 is a similar view of the same slightly modified to produce a stop in the finished band for the purpose hereinafter explained; Fig. 8 is a plan view of the tubular band made from the strip of Fig. 6, and Fig. 9 is a similar view of such a band made from the strip of Fig. 7; Fig. 10 is a plan view of the band of Fig. 9 showing, somewhat exaggerated, the crimped condition to which it is reduced by fastening it about the skirt of a sealing cap on a bottle as in Fig. 5; Fig. 11 is an endless fastening band of mere wire,

and Fig. 12 shows, also somewhat exaggerated, the crimped condition of the same produced by fastening it in its operative position; Fig. 13 is a view, like that presented in Fig. 11, of an endless fastening band formed of sheet metal; Fig. 14 shows the band of Fig. 13 in the likewise exaggerated crimped condition to which it is reduced by fastening it about the skirt portion of a bottle-sealing cap. Fig. 15 is a sectional view through the bottle or jar taken at the plane occupied by the fastening band; Fig. 16 is a perspective view of the cap after its application to the bottle; Fig. 17 is a view showing the closure before the skirt portion is folded therefrom, the lines along which the sheet material forming the closure folds being dotted; Fig. 18 is a view on an enlarged scale looking from the bottom of the closure cap before it is tightened; Fig. 19 is a view from the top of the portion shown in Fig. 18; Fig. 20 is a bottom view showing the folds of the closure cap more closely approached; and Fig. 21 is a perspective view of the cap before its application to the bottle.

Like parts are indicated by similar characters of reference throughout the different figures.

The cap or closure 15 shown may be best formed of comparatively heavy paper, though any other suitable flexible material may be employed, and it is preferably reduced to a permanent cap form ready for application to seat over and cover the mouth of a bottle and encircle the neck, represented at 17 (Figs. 4 and 5), though it may be a flat piece of the material adapted to be folded into cap shape over the bottle mouth and about its neck portion, either way providing the skirt portion 16 of the cap, with the advantage in the prepared cap of enabling it to be provided about the free edge of the skirt portion with a seating flange 18 for the fastening band hereinafter described.

With a formed cap applied to a bottle and encircled by a band of flexible non-resilient metal and of any suitable type, including any of the types illustrated, the band is squeezed or compressed in place to tighten it about the bottle neck and fasten about the same the skirt portion of the cap, thus sealing the bottle. This operation may be readily performed by inserting the bottle neck into and operating against it a suitable machine, such as that illustrated in Fig. 1 and denoted, as a whole, by the reference character 20. It involves an annular table 21 on which is rotatably confined a ring 22 provided with an operating handle 23 and containing, at equal intervals apart, similar oblique slots 24; and from a point adjacent to the inner end of each slot, a rigid bearing 25 projects radially from the inner edge of the annular bed toward its center. In each

bearing is reciprocally supported a similar plunger 26 provided near its outer end with a stud 27 engaging the adjacent cam slot 24 and terminating at its inner end in a head 28 presenting an arc-shaped face. These heads form about the center of the machine a sectional annulus through which a bottle neck may be inserted, as by introducing it into the machine from underneath the table 21. With a bottle neck in the aforesaid annulus and equipped with a band-encircled cap 15, by turning the handle 23 to rotate the ring 22 into the position represented in Fig. 1, the engagement of the cam slots 24 with the studs 27 advances the plungers 26 simultaneously and uniformly to clamp the band between the heads 28 and fasten it securely in place as hereinafter described; and turning the handle in the opposite direction effects withdrawal of the plungers and release of the bottle.

As will be understood, dealers in the material contained in the bottles will be equipped with machines, such as the machine 20, for sealing them and also, by preference, with supplies of the caps 15 which are adapted by their flaring shape to be shipped to them in nested condition with a band 19 about each and bearing against the flange 18, ready for applying the cap in place and subjecting the band to the action of the machine. A desirable type of the band is that shown in Fig. 8, which is produced from a sheet metal strip 19¹ (Fig. 6) by bending it lengthwise upon itself into a tapering tube and reducing this tube into circular form with the narrower end telescoping the wider end. In subjecting this band to the action of the machine 20, the encircling plungers compress it about the skirt of the sealing cap to tighten it against the latter, thereby forcing and wedging the narrower end into the wider end of the annular tube in addition to crimping the band. This same type of band may be produced in the form represented in Fig. 9 from the tapering sheet metal strip 19² of Fig. 7, which differs from that of Fig. 6 in containing an offset in its narrower end portion. This offset presents, in the band of Fig. 9, a shoulder 19³ forming a stop which prevents the action of the machine from driving the narrower into the wider end of the tubular band, so that when the plungers 26 are caused to exert their pressure against this band, which should be set in the machine to bring the telescoping sections into the path of one of the plunger heads, the exertion by the heads of the circumferential compression on the band will crimp it into the shape or approximately the shape illustrated in Fig. 10, one of the crimps being formed at the telescoping joint to clinch it as represented at 19⁴. The bands of Figs. 11 and 13 are endless, the first named being 130

formed of non-resilient wire of round cross section and the other of sheet metal. Obviously, being endless as is, practically, the band of Fig. 9, the compression action upon them of the plungers in the machine will crimp them as represented by the wire band of Fig. 12 and by the sheet metal band of Fig. 14. In every instance, however, the non-resilient band is tightened by squeezing it about the cap skirt to fasten the cap into sealing condition upon the bottle. By making the bands of nonresilient metal the bands hold their shape after being placed into engagement with the closure skirt. When the bands are made hollow as described they are nonresilient. If the metal of the band was resilient it would not perform its closure holding function satisfactorily. The nonresilient character of the band therefore is an important feature of our invention. The bottle or jar, and in the claims we use the term bottle in the broad sense of a bottle or jar, is beaded at its mouth or outwardly extended adjacent its mouth so that the inner surface of the lower part of the skirt of the cap may be contracted sufficiently to be overhung by the top of the bottle whereby the cap cannot be lifted from the bottle without the enlargement of the non-resilient band. If this band is enlarged its function as a protecting seal is destroyed so that the bottle may not again be filled without detection. This mode of fastening the cap in place renders it readily removable for emptying the contents of the bottle, since to free it all that is required is to force the band, as with a fork or other suitable implement applied to any point thereon, past the flanged edge of the cap, thereby permitting the cover to be readily pulled or torn off; or, if desired, the crown portion of the cap may be cut away, thus opening the bottle without disturbing the band.

Our improvement is peculiarly effective in its purpose in connection with bottles with circumferentially beaded mouths like the representations in Figs. 4 and 5, since, in compressing the band in the manner described, it tends to stretch the cap skirt about the bead and thus draw the cap tautly over the bottle mouth, thereby effectually sealing the bottle because of the closeness and unyielding character of the seal rendered so by compressing the non-resilient band as described.

In Figs. 15 to 21 inclusive, the closure is shown in the form of a flexible fiber, paper or pasteboard structure having the form of an inverted dish whose skirt portion is flattened or folded in a manner to provide recesses 29 between adjacent folds, the sides of said recesses converging to points at the top of the closure and diverging toward the bottom of the closure,

whereby these sides of the recesses are brought close together when the tightening band is gripped about the skirt portion of the closure. The folds in the skirt portion of the closure are desirably formed as illustrated to constitute a sinuous line of continuously connected U-shaped gatherings, whereby, when the sides of the recesses 29 are brought close together, three thicknesses or layers of the material of the closure are provided between the tightening band and the neck of the bottle, whereby the material of the closure is suitably thickened or augmented where the tightening band is located in order that the tightening band may be embedded in the amplified portion of the closure so as thoroughly to seal the bottle where the tightening band is located to prevent the passage of fluid between the interior of the bottle and the exterior thereof, any moisture to which the closure may be subject serving further to amplify the thickness of the closure where the band is located, still further to enable the tightening band to be embedded within the material of the closure and improving the fluid tight connection between the closure and the bottle where the band is located. The portion of the closure below the band is obviously thicker than the portion of the closure immediately underlying the band, so that the removal of the closure past the band is rendered difficult. There are recesses 30 upon the interior of the closure that also taper to vanishing points at the top of the closure, whereby open spaces between the folds are avoided where the top of the closure engages the bottle mouth, whereby the top of the closure is unprovided with internal passages or recesses where such top of the closure engages the mouth of the bottle, in order further to restrict or obstruct fluid passage between the interior and exterior of the bottle. We consider it to be broadly new with us to provide a closure in which the thickness of the skirted portion is amplified and in which such thickened portion co-operates with a tightening band of such a character that it may be embedded in the thickened portion of the closure to accomplish the results which have been described, and while we prefer to amplify the thickness of the closure in the manner described, we do not wish to be limited to the precise construction shown, as obviously the closure may be otherwise thickened to accomplish the object desired.

In the preferred embodiment of our invention, we not only cause the clamping ring to force the closure into tight engagement with the bottle neck, but we also kink or crimp or convolute the non-resilient tightening ring in such a manner as to pinch an outsetting gathered portion or

portions 31 of the closure so as to enable the tightening ring positively to grip the closure and prevent accidental withdrawal thereof from the bottle, thereby supplementing the hold which the tightening ring has upon the skirted portion of the closure due to the embedding of the tightening ring within the thickened portion of the closure. We prefer to provide a plurality of outsetting gathered portions 31 distributed about the bottle and which are thus pinched or gripped by the kinks or folds in the tightening ring, but we do not wish to be limited to the number of such outsetting gatherings 31 that are employed. The closure, as made in accordance with the preferred embodiment of our invention, and the tightening ring that is to be applied thereto, may be subjected to the action of the machine illustrated in Fig. 1 in order that the tightening band or ring may have formed therein the gripping loops that engage the outsetting closure gatherings 31, these closure gatherings being formed when the machine is operated to locate the closure and the tightening band in place about the bottle neck, portions of the skirt of the closure that are displaced as the result of the mutual approach of the parts of the head 28 being pressed between these parts and there finding access between the sides of the loops in the tightening ring, which loops are also formed as a consequence of the displacement of the material of the tightening ring between the sections of said head.

What we claim as new and desire to secure by Letters Patent is:—

1. In combination with a receptacle, means for sealing it, comprising a cap of flexible material covering the mouth of the receptacle with its skirt portion extending about the portion of the receptacle having the receptacle mouth, and a tubular crimped band of flexible metal tapering toward one end with the narrower end telescoping the wider, said band tightly encircling said skirt portion, for the purpose set forth.

2. A fastener for skirted bottle caps and the like comprising a tubular wire-like ring of substantially non-resilient material adapted to be pressed into sealing engagement with a cap, substantially as described.

3. A fastener for skirted bottle caps and the like comprising a tubular wire-like ring of substantially non-resilient material adapted to be pressed into sealing engagement with a cap, the ends of the rings telescoping to permit varying the diameter of the ring.

4. The combination with a bottle or the like having an outsetting lip or bead; of a skirted cap for the mouth of said bottle; and a tubular wire-like ring of substantially non-resilient material compressing the skirt-

ed portion of said cap into engagement with the bottle beneath said bead whereby a portion of the cap skirt underlies the bead.

5. A fastener for skirted bottle caps and the like comprising a tubular wire-like ring, of substantially non-resilient material having outstanding ribs, substantially as and for the purpose described.

6. A fastener for skirted bottle caps and the like comprising a ring of substantially non-resilient material having outstanding ribs, substantially as and for the purpose described.

7. A fastener for skirted bottle caps and the like comprising a split ring of substantially non-resilient material adapted to be pressed into sealing engagement with the cap and capable of maintaining a reduced diameter independently of extraneous attaching means for the terminal portion of said ring.

8. A fastener for skirted bottle caps and the like comprising a tubular wire-like ring, of substantially non-resilient material having outstanding ribs, in combination with the cap having portions thereof gripped within said ribs.

9. A fastener for skirted bottle caps and the like comprising a ring of substantially non-resilient material having outstanding ribs, in combination with the cap having portions thereof gripped within said ribs.

10. A fastener for skirted bottle caps and the like comprising a tubular wire-like ring of substantially non-resilient material adapted to be pressed into sealing engagement with a cap, the ends of the rings telescoping to permit varying the diameter of the ring, said ring being formed of a tapering strip of metal to provide an enlarged receiving portion for the relatively reduced opposite end.

11. A fastener for skirted bottle caps and the like comprising a tubular wire-like ring, of substantially non-resilient material having outstanding ribs, said ring being formed of a tapering strip of metal to provide an enlarged receiving portion for the relatively reduced opposite end.

12. A fastener for skirted bottle caps and the like comprising a tubular wire-like ring, of substantially non-resilient material having set portions projected out of the normal plane of the ring.

13. A fastener for skirted bottle caps and the like comprising a ring of substantially non-resilient material having set portions projected out of the normal plane of the ring.

14. A blank for a tubular fastening device adapted to serve as a sealing means for skirted bottle caps and the like, comprising a strip of substantially non-resilient metal tapering toward one end to provide an en-

larged tubular receiving terminal portion and a relatively reduced opposite tubular terminal portion.

15. The combination with a bottle and its 5 cap of flexible material, of a ring embracing said cap and forcing the same circumferentially into sealing engagement with the bottle neck, portions of the ring gripping corresponding parts of the material 10 of the cap in addition to the circumferential binding action of the ring.

16. The combination with a bottle, of a flexible cap therefor having a skirt portion fluted therearound, the extent of the same, 15 to give the skirt a substantial and uniform thick character relative to the remaining

portion of the cap, and a ring engaging said fluted skirt to bind the same into sealing engagement with the mouth portion of the bottle, such binding action flattening the 20 fluted portions engaged thereby to cause the skirted portion below the ring to protrude therebeyond to assist in preventing escape of the cap from the ring.

In witness whereof, we hereunto subscribe 25 our names this eleventh day of June, A. D., 1910.
